LOUIS N. D. WILLIAMS, OF OGONTZ, PENNSYLVANIA, ASSIGNOR TO SCOTT & WILLIAMS, INCORPORATED, OF NEW YORK, N. Y., A CORPORATION OF MASSACHUSETTS

MECHANISM FOR TRANSFERRING KNITTED WEBS

Application filed December 12, 1923. Serial No. 680,063.

This invention relates to mechanism useful in connection with knitting machines in transferring the stitches or loops of knitted webs, and more particularly to a type of mechanism whereby knitted webs may be transferred to the needles of knitting machines as practiced for example in stocking manufacture when ribbed tops of half-hose are "run on" so that the leg and foot portions may be knit in integral prolongation.

The object of my invention is to enable the transfer of knitted webs to be accomplished in an expeditious manner without necessitating manual manipulation, and to provide a simple and efficient means to this end whereby the possibilities of stitch dropping, distorting of the fabric loops and straining the needles of the knitting machine are entirely obviated so that a clean union between the transferred web and the first course of the knitting is assured.

In carrying out my invention, I employ means by aid of which a transfer device may be moved into transfer position, contiguous to the needles of a knitting machine, with its stitch points in accurate alignment and registry with the needles; associated means whereby the points and the needles may be relatively shifted, en masse, into mutual engagement; and means whereby the fabric stitches or loops may be subsequently simultaneously advanced from one to the other.

In substantiation of the foregoing introductory remarks, I will now proceed to describe an organization conveniently embodying the novel features of this invention.

In the drawings Fig. I is a top plan view of a transfer device in the form of a point ring which I employ in the practice of my invention in connection with a circular knitting machine.

Fig. II is an elevation of portion of a standard circular knitting machine with my improved transfer mechanism applied, the transfer ring being shown in section so as to more clearly set forth certain important details.

Fig. III is an illustration, similar to the preceding, showing the carrier for the trans-

fer ring swung to active position, with the ring poised above the needle cylinder of the knitting machine, in readiness for effecting the transfer operation.

Fig. IV is a sectional view, taken as indicated by the arrows IV—IV in Fig. III, illustrative of my improved transfer mechanism and associated parts of the knitting machine except as to a conventional representation of the needles having been omitted for the sake of simplicity.

Figs. V and VI are views, similar to Figure IV, showing successive steps in the manipulation of the transfer mechanism.

Figs. VII, VIII, and IX, are enlarged detail views showing the relation of the points of the transfer ring to the needles of the knitting machine corresponding to the positioning of the parts of the mechanism as represented respectively in Figs. IV, V and VI; and,

Fig. X is a detail view showing a modified form of point which may be used in lieu of the type shown in the other illustration.

Referring first to Figs. I, II and III of these drawings, it will be noted that the transfer ring comprises an annular shell 1 having at one end a circumferential enlargement or head 2 from which project a multiplicity of fluted stitch points 3 preferably arranged as a convergent annular series, as shown. Hereinafter, while I employ the term "points", in order to avoid alternatives, it is to be expressly understood such term is intended to comprehend all analogous elements associated in transfer devices of the typified character. Slidably guided for independent motion relative to the shell 1 is a sleeve 4, from the outer end of which extend radially a series of strippers 5 that project through the intervals between the points 3. Disposed diametrically across the shell 1 is an actuating bar 6 and parallel thereto, as well as normally in the same plane therewith, is a similar bar 7 which extends diametrically across the base of the stripper sleeve 4, see Fig. IV, the latter being notched as at 9 to clear the bar 6. The shell 1 is further provided with a number of leg or

relatively pendent projections 8 for a purpose to be later described.

The knitting machine as herein illustrated comprises a bed plate 10, and a needle cylinder 11, having in its periphery a series of longitudinally disposed slots or grooves for guidance of needles 12, shown as of the ordinary pivoted latch type. The needle cylinder 11 is surrounded, near the top, by the usual sinker ring 13. Rising from the bed plate 10 at one side of the needle cylinder 11, is a bracket post 14 whereto is pivotally mounted at 15, a carrier 16 for the transfer ring which is swingable toward—and away from—said needle cylinder. As shown, this carrier 16 is in the form of an arm having an angular profile configuration and terminating in an annulus 17 from one face of which projects a circular flange boss 18. The carrier 16 is sustained in the retracted position, shown in Fig. II, by engaging with a fixed abutment 19 projecting from the bracket 14 while its inner position is determined by a stop 17^a arranged to engage a part of the needle cylinder 11, preferably on top of the ledge afforded by the sinker ring 13, as shown in Fig. III.

The boss 18 is beveled, as at 20, to facilitate mounting thereover the shell 1 of the transfer ring annular shell 1 which is thus held against lateral displacement in an inverted position on the annulus 17. The circumferential position of the transfer ring annular shell 1 is determined by cooperation of a notch in the edge of said shell with a projection 21 on the annulus 17. The side of the annulus 17 opposite that occupied by the boss 18 is bridged by a cross piece 22, from which projects a bearing boss 23 that is axially bored to receive and guide a reciprocating plunger 24 terminating at its outer end in a ball handle 25. This plunger 24 is influenced by a helical spring 26 in compression between the outer end of the bearing boss 23 and the handle 25; outward movement of the plunger being limited by means, such as a collar 27, adapted to abut against the inner face of the bridge piece 22. Pivotally mounted to the carrier 16 at the inner periphery of the flange boss 18, is a follower or trigger 28 which normally lies in the path of the plunger 24, and when the transfer ring is in position on said carrier overlies the actuating bars 6 and 7 respectively of the shell 1 and sleeve 4 of the transfer ring, as clearly shown in Figs. II, III, IV and V. To the inner end of the plunger 24 is pivotally hung a hook 29 adapted, when the transfer ring is moved to position over the needle cylinder 11, to swing beneath the actuating rods 6 and 7. The hook 29, it will be observed from Figs. IV, V and VI, is counterweighted at one side so as to fall away from the rods 6 and 7 as the car-

rier is moved to the retracted position of Fig. II.

As a means for locking the transfer ring to prevent its dislodgment as the carrier 16 is swung to transfer position over the needle cylinder 11, I provide a latch 30 which is pivoted to the carrier 16 at 31 and designed to engage a notch or aperture 32 in the shell 1 of the transfer ring under yielding influence of a leaf spring 33 secured to a lateral boss 34 of the carrier 16. When the carrier 16 is in its retracted position the latch 30 is maintained withdrawn by virtue of its engagement with a stop 35 extending from the abutment 19 previously described, so that the transfer ring may be readily placed on, or removed from said carrier.

For the purpose of preventing rotative movement of the needle cylinder 11 during the transfer operation, I provide a locking pin 36 adapted to enter an aperture in the top face of the driving gear 37 whereon the needle cylinder 11 is mounted, but which is normally held retracted by a helical spring 38 that surrounds the same. In order to effect such locking of the cylinder 11 automatically during inward swinging of the carrier 16, the fulcrum hub of the latter is formed with an eccentric cam surface 39 that induces downward motion of a plunger 40, guided for reciprocation in a lug 41 on the bracket 14, and which in turn transmits the motion received, through a pivoted arm 42, to the locking pin 36.

Transfer is effected in accordance with my invention as follows:

The transfer ring with the knitted web mounted thereon is placed upon the carrier 16 when the latter is in the retracted position shown in Fig. II, proper positioning both laterally and circumferentially being determined through guidance of the boss 18 and cooperation of the projection 21 with the notch in the shell 1. The knob 25 is thereupon grasped, and, immediately upon the initiation of the inward swing of the carrier 16, the latch 30 clears the stop 35 and is, as a result, urged inwardly by the spring 33 to engage the aperture 32 of the shell 1 of the transfer ring, thereby locking the latter to the carrier 16. When the carrier 16 has been swung inwardly to the full extent as determined by the stop 17^a, the transfer ring is supported in transfer position axially of and above the needle cylinder 11 with its points 3 contiguous to, and aligned with the knitting needles 12, as shown in Figs. III, IV and VII. Also concurrently with the inwardly movement of the carrier 16, the locking pin 36 is depressed as shown in Fig. III to hold the needle cylinder 11 against rotation during subsequent manipulations of the transfer mechanism. The plunger 24 is thereupon depressed in opposition to the spring 26 its movement being communicated

to the trigger 28 and in turn by the latter to the actuating bars 6 and 7 so that the shell 1, with the stripper sleeve 4, of the transfer ring are simultaneously moved relative to the carrier 16 toward the needle cylinder 11, the latch 30 incidentally yielding to forced displacement from the aperture 32. This movement continues until the trigger 28 swings clear of the end of the plunger 24 at which time the feet 8 of the shell 1 encounter the top of the sinker ring 13 on the needle cylinder 11 to determine the proper co-ordinative engagement of the points 3 with the needles 12, as shown in Fig. VIII. In further movement of the plunger 24 the rod 7 of the stripper sleeve 4 alone is engaged and the strippers 5 consequently advanced to effect stripping of the fabric stitches from the points 3 and their transference to the needles 12, as clearly shown in the enlarged view of Figure IX.

Upon release of the ball handle 25 on the plunger 24 after completion of the transfer, the parts of the transfer ring are automatically restored to their original positions relative to each other and to the carrier arm 16 as follows:

From Fig. VI it will be observed that the spring 26 in its effect upon the plunger 24 will cause the hook 29 to lift the bar 7 thereby bringing the stripper sleeve 4 back to its normal position in the shell 1 of the transfer ring, and in continued movement of the plunger 24, said hook will likewise engage the actuating bar 6 thereby restoring the shell 1 to its original position on the carrier 16, the latch 30 slipping back into the aperture 32, and the boss 18 serving the while as a guide for said shell. The carrier 16 is then swung to the retracted position of Fig II, and, as it nears the limit of this movement the latch 30 in engaging the stop 35 is withdrawn from the aperture 32 in the shell 1, and at the same time the hook 29 falls away from the rods 6 and 7 so as to leave the transfer ring free for ready removal from the carrier 16 so that another web may be placed upon it, or another ring substituted therefor, in readiness for a succeeding transfer operation. Also coincidentally with the retractive movement of the carrier 16 and attendant positional change of the cam 39 the locking pin 36 is permitted to rise under the action of its spring 38 thereby to release the needle cylinder 11 so that the machine may be started to complete the stocking.

The modified type of point shown at 45 in Fig. X differs from the type of the other illustrations in that it is fluted or slotted only in its outer end thus affording an internal shoulder 46. When points 45 of the modified type are employed in the transfer ring, the feet 8 may be entirely dispensed with, since the downward movement of the shell 1 during transfer will be properly de-

termined when the shoulders 46 of said points come to rest against the needle tops, as shown in the illustration.

Wherever in the appended claims, the term "stitches" appears, it is to be understood that the same is employed in its broadest sense and refers not only to true "stitches" but to "loops" as well, and in fact, any bight of yarn capable of being acted upon as a "stitch."

Having thus described my invention, I claim:

1. Mechanism for transferring knitted webs including a transfer device comprising a multiplicity of stitch points and associated independently movable stripper means; in combination with carrier means for supporting the transfer device with its points in alignment with the needles of a knitting machine, means for shifting the transfer device to bring its points into engagement with the knitting needles for stitch transfer and thereafter moving the stripper means to displace the fabric stitches from the points, and means for automatically restoring the stripper means to the original position in the transfer device and the device on the carrier at the completion of the transfer operation.

2. Mechanism for transferring knitted webs including a transfer ring comprising an annular shell provided with a series of projecting stitch points also a diametrical actuating bar, and an independently movable sleeve provided with strippers adapted to cooperate with the points, said sleeve also having a diametrical actuating bar; in combination with a carrier for supporting the transfer ring above the needle cylinder of a circular knitting machine with the points in alignment with the needles, a manipulating plunger on the carrier, a trigger pivoted to the carrier normally in the path of the plunger and overlying the diametrical actuating bars aforesaid, whereby, as the plunger is depressed, both bars are advanced to simultaneously effect movement of the shell of the transfer ring and its associated stripper sleeve to shift the points into engagement with the knitting needles, and in continued movement of the plunger, after the trigger has swung clear of the same, the actuating bar of the stripper sleeve alone is engaged and the sleeve independently advanced to strip the fabric stitches from the points.

3. Mechanism for transferring knitted webs including a transfer ring provided with an annular series of stitch points also a diametrical actuating bar; in combination with carrier means for supporting the transfer ring above the needle cylinder of a circular knitting machine with the points in alignment with the needles, plunger manipulating means adapted to engage the actuating bar of the transfer ring to move the same relative to the carrier for the purpose of

- bringing the points into engagement with the knitting needles for stitch transfer, a hook on the plunger adapted to engage beneath the actuating bar, and a spring operative upon the plunger to automatically restore the transfer ring to its original position on the carrier when the plunger is released at the completion of the transfer operation.
- 10 4. Mechanism for transferring knitted webs including a transfer ring provided with an annular series of stitch points also a diametrical actuating bar; in combination with a swingable carrier for moving the transfer ring from an inverted retracted position to transfer position over the needle cylinder of a circular knitting machine, a spring influenced manipulating plunger on the carrier for engaging the actuating bar of the transfer ring to shift the latter relative to the carrier in transferring the fabric stitches, a pivoted hook adapted to engage said actuating bar to effect automatic restoration of the transfer ring to its original position on the carrier upon release of the plunger to the spring action, said hook being counterweighted so as to fall away from the bar as the carrier is retracted to permit removal of the transfer ring from the carrier.
- 15 5. Mechanism for transferring knitted fabrics including a transfer ring comprising an annular shell provided with a series of projecting stitch points also a diametrical actuating bar, and an independently movable sleeve provided with strippers adapted to cooperate with the points, said sleeve also having a diametrical actuating bar; in combination with a carrier for supporting the transfer ring above the needle cylinder of a circular knitting machine with the points in alignment with the needles, a manipulating plunger on the carrier, a trigger pivoted to the carrier normally in the path of the plunger and overlying the diametrical actuating bars aforesaid, whereby, as the plunger is depressed, both bars are advanced to simultaneously effect movement of the shell of the transfer ring and its associated stripper sleeve to shift the points into engagement with the knitting needles, and in continued movement of the plunger, after the trigger has swung clear of the same, the actuating bar of the stripper sleeve alone is engaged and the sleeve independently advanced to displace the fabric stitches from the points, hook means attached to the plunger and adapted to engage beneath the actuating bars, and a spring operative upon the plunger so that as the latter is released at the completion of the transfer operation, the stripper sleeve is automatically restored to its original position in the transfer device, and said device to its original position on the carrier.
- 20 6. Mechanism for transferring knitted webs including a transfer ring comprising an annular series of stitch points, in combination with carrier-means for swinging the transfer ring from an inverted location into transfer position over the needle cylinder of a circular knitting machine with the points in alignment with the needles thereof, means to automatically lock the transfer device to the carrier during swinging movement of the latter, means for temporarily holding the transfer ring properly aligned over the needles, means for bodily moving the transfer ring to bring the points into engagement with the knitting needles, and means pendant to the transfer ring adapted to engage the needle cylinder to limit movement of said ring.
- 25 7. Mechanism for transferring knitted webs including a transfer ring comprising an annular series of stitch points, in combination with carrier-means for swinging the ring from an invert retracted position into transfer location above the needle cylinder of a circular knitting machine with the points in alignment with the needles thereof, means to automatically lock the transfer device to the carrier during swinging movement of the latter, means for temporarily holding the transfer ring directly aligned over the needles, means for bodily moving the transfer ring to bring the points into engagement with the needles, and a number of projections on the ring adapted to engage with a protruding ledge of the needle cylinder to limit the movement of said ring.
- 30 8. Mechanism for transferring knitted webs including a transfer device with a multiplicity of stitch points, in combination with vertically-swingable carrier-means for moving the transfer device from an invert retracted location into position with its points in alignment with the needles of a knitting machine, means to automatically lock the transfer device to the carrier during swinging movement of the latter, means for temporarily holding the transfer ring properly positioned over the needles, means for bodily moving the transfer device relative to the carrier to bring the points simultaneously into engagement with the knitting needles for stitch transfer, and means for automatically restoring the transfer ring to its original position on the carrier at the completion of the transfer operation.
- 35 9. Mechanism for transferring knitted webs including a transfer device comprising a multiplicity of stitch points, in combination with vertically-swingable carrier means for moving the transfer device from an inverted location into transfer position over the needles of a knitting machine, and a spring-influenced locking-pin adapted to hold the needle cylinder in locked position while the transfer device is in the transfer position.

10. Mechanism for transferring knitted webs including a transfer device comprising a multiplicity of stitch points, in combination with vertically-swingable carrier-means for moving the transfer device from an inverted location into transfer position over the needles of a knitting machine, a plunger pin cooperative with the needle cylinder driving gear, and cam means adapted to depress said pin into the driving gear to lock the same against rotation while the transfer device is in transfer position.
11. Mechanism for transferring knitted webs including a transfer device comprising a multiplicity of stitch points, in combination with vertically-swingable carrier-means for moving the transfer device from an inverted location into transfer position over the needles of a knitting machine, means to automatically lock the transfer device to the carrier during swinging movement of the latter, a plunger pin co-operative with the needle cylinder driving gear, cam means adapted to depress said pin into locking engagement with the driving gear, and spring means serving to retract the plunger from such locking position.
12. Mechanism for transferring knitted webs including a transfer device comprising a multiplicity of stitch points, in combination with vertically-swingable carrier-means for moving the transfer device from an inverted location into transfer position over the needles of a knitting machine, and means comprising a spring influenced pin with co-operative means actuated by a cam surface on the fulcrum hub of the swingable carrier aforesaid to lock the needle cylinder against rotation as the carrier means is swung to transfer position.
13. Mechanism for transferring knitted webs including a transfer device comprising a multiplicity of stitch points, in combination with vertically-swingable carrier-means for moving the transfer device from an inverted location into transfer position over the needles of a knitting machine, a spring influenced lock pin adapted to engage the needle cylinder driving gear, a co-operative arm pivoted to the carrier sustaining bracket, and a plunger swept by an eccentric cam on the fulcrum hub of the swingable carrier aforesaid whereby the needle cylinder is secured against rotation as the carrier means is swung to transfer position.
14. Mechanism for transferring knitted webs including a transfer device comprising a multiplicity of stitch points, in combination with vertically swingable carrier means for moving the transfer device from an inverted location into transfer position over the needles of a knitting machine, and cam actuated plunger means adapted to positively arrest rotation of the needle cylinder

prior to inversion of the transfer device into actual transfer position.

In testimony whereof, I have hereunto signed my name at Philadelphia, Pennsylvania, this 6th day of December, 1923.

LOUIS N. D. WILLIAMS.
